UNITED STATES PATENT OFFICE.

CELESTIN GUILMART, OF GOSHEN, CONNECTICUT.

SLUICE.

Specification of Letters Patent. Patented May 13, 1919.

1,303,295.

Application filed February 24, 1917. Serial No. 150,789.

To all whom it may concern:

Be it known that I, CELESTIN GUILMART, a citizen of the United States, residing at Goshen, in the county of Litchfield and State 5 of Connecticut, have invented certain new and useful Improvements in Sluices, of which the following is a specification.

This invention relates to sluices, and more particularly to a sluice or drain for roads:

10 One of the main objects of the invention is to provide a sluice of simple construction and operation which is adapted to be placed in a road so as to prevent washing of the same. A further object is to provide a sluice 15 so constructed as to direct the water from the crown of the road into the gutter, and adapted to be quickly and easily secured in the proper position in the road. A further object is to provide a sluice which can be 20 produced at relatively small cost. Further objects will appear from the detailed description.

In the drawings:

Figure 1 is a top plan view of the sluice 25 with the grating applied,

Fig. 2 is a section on line 2—2 of Fig. 1,

Fig. 3 is a top plan view of a sluice with the grating removed,

Fig. 4 is a section on line 4—4 of Fig. 1,

30 Fig. 5 is a fragmentary detail sectional view of the bracket for securing the sluice in position.

The sluice is provided with a central longitudinally extending trough 1 mounted between the two horizontal side plates 2 and 2^a. The plates 2 and 2^a and trough 1 are supported by transversely extending supporting beams 3, 4, and 5. The plate 2^a is provided with a plurality of spaced transversely extending arcuate grooves 6 which communicate at their inner ends with the trough 1. Certain of these grooves, as 6^a, are cut away at their inner ends to provide semi-elliptical openings 7 extending through 45 the side of trough 1.

In using my sluice, it is secured in the road with the upper or broader end extending slightly beyond the wheel track, and is directed downwardly from the crest or 50 crown of the road toward the gutter. The water which normally collects in the wheel track flows over the plates 2 and 2^a into the central trough 1 down which it flows into the gutter. The plate 2^a will be placed toward the higher point of the road, in the 55 case of a road on a hill or incline, so that the

grooves 6 and 6^a will provide means whereby the drainage can easily enter the central trough 1. The openings 7 provide a series of traps which will receive and retain 60 heavier articles, such as pebbles and small stones, which might tend to stop the trough 1 and thus interfere with the proper flow of drainage through the same. As will be noted, when the sluice is in operative position, the grooves 6^a with which the openings 7 communicate will be positioned closely adjacent the wheel track where the greater number of heavier articles such as pebbles 65 and the like will be most apt to be knocked 70 or washed into the sluice.

For securing the sluice in operative position, an angle bracket 8 has one arm 8^a provided with a vertically extending slot 9 through which is passed a bolt 10 secured 75 in the supporting beam 5 of the sluice adjacent one corner thereof. The other arm 8^b of the angle bracket 8 is adapted to be secured by a screw bolt 11 to a block or stone 12 which is set in the road a suitable 80 distance below the surface of the same. The arm 8^b of the angle bracket is provided, contiguous with the arm 8^a, with a transversely extending groove which receives an adjusting block or strip 13. This strip is adapted 85 to engage the underface of the bolt 10 and serves to adjust the sluice relatively to the block 12, thus providing means whereby, by providing strips of different widths, the inclination of the sluice can be varied. The 90 sluice is set in the road so as to bring its upper surface approximately flush with the upper surface of the road.

A suitable shaped relatively heavy grating 14 is provided with downwardly extending side pieces 15 which fit snugly about the plates 2 and 2^a. This grating serves to protect the sluice proper from injury due to vehicles passing over the same, without in any way interfering with the flow of drainage to and through the sluice.

What I claim is:

1. A sluice comprising spaced side portions, and having a series of transverse parallel depressions, a trough common to said depressions at the inner ends of the latter, and a grating over said trough and supported by the sides.

2. A sluice comprising spaced sides, one of said sides being longer than the other, a tapered trough supported by said sides and having a plain portion and a series of trans-

verse parallel grooves in its opposite portion, a central longitudinal depression with which the inner ends of the grooves communicate, certain of said grooves inclining toward the trough and having openings communicating therethrough, and a grating over the trough.

3. In a sluice, the combination of two spaced tables, and a longitudinally extending trough mounted between the tables and open at one end, one of said tables being provided with a plurality of spaced transversely extending grooves communicating with the trough, and said trough being provided with a plurality of spaced openings through one side communicating with certain of said grooves.

4. In a sluice, the combination of two spaced tables, a longitudinally extending trough mounted between the tables, one of said tables being provided in its upper face with a plurality of spaced transversely extending grooves communicating with the

trough, and means carried by the sluice for securing the same in operative position at 25 an inclination and for adjusting the inclination of the sluice.

5. A sluice comprising spaced sides, one of said sides being longer than the other, a tapered trough supported by said sides and 30 having a plain portion and a series of transverse parallel grooves in its opposite portion, a central longitudinal trough with which the inner ends of the grooves communicate, certain of said grooves inclining 35 toward the trough and having openings communicating therethrough, a grating over the trough, means for bracing the center of the trough and means for adjusting the inclination of the sluice.

In testimony whereof I affix my signature in presence of two witnesses.

CELESTIN GUILMART.
